(57) **CLAIM**

The ornamental design for a display screen or portion thereof with a graphical user interface, as shown and described.

DESCRIPTION

The patent file contains a least one drawing executed in color. Copies of this patent with color drawing(s) will be provided by the Office upon request and payment of the necessary fee.

FIG. 1 is a front view of a first image in a sequence for a display screen or portion thereof with a graphical user interface according to a first embodiment;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and

FIG. 8 is an eighth image thereof;

FIG. 9 is a front view of a first image in a sequence for a display screen or portion thereof with a graphical user interface according to a second embodiment;

FIG. 10 is a second image thereof;

FIG. 11 is a third image thereof;

FIG. 12 is a fourth image thereof;

FIG. 13 is a fifth image thereof;

FIG. 14 is a sixth image thereof;

FIG. 15 is a seventh image thereof; and,

FIG. 16 is an eighth image thereof.

The outermost broken lines showing a display screen or portion thereof illustrate portions of the article and form no part of the claimed design. The masked area outside the dot-dash broken line boundary forms no part of the claimed design. The appearance of the graphical user interface transitions sequentially between the images shown in FIGS. 1-8 in embodiment 1 and FIGS. 9-16 in embodiment 2. The process or period in which one image transitions to another forms no part of the claimed design.
